Philadelphia, Pa.

Application August 3, 1942, Serial No. 453,423

4 Claims. (Cl. 89—3)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to firearms.

An object of this invention is to provide a firearm of the type shown in Browning Patent 1,293,021, with means incorporated therein for assuring a minimum amount of gun failure due to cartridge case extraction difficulties.

Another object of the invention is to provide a firearm of the U. S. standard Browning machine gun type, with means therein for assuring that the breech bolt and cartridge are in their farthest rear locked positions with respect to the barrel before the cartridge is fired.

Another object of this invention is to provide means in a firearm for assuring a minimum amount of gun failure due to excessive deformation of fired cartridge cases.

Another object of this invention is to provide means in a firearm for assuring minimum and predetermined deformation of fired cartridge cases.

The specific nature of the invention as well as other objects and advantages thereof will clearly appear from a description of a preferred embodiment as shown in the accompanying drawing in which:

Fig. 1 is a view in longitudinal section of a machine gun.

Fig. 2 is an enlarged view of modified bolt and barrel extension members similar to those shown in Fig. 1 and showing in greater detail the assembly of spring means between the bolt and barrel extension.

Fig. 3 is a section taken substantially on line 3—3 of Fig. 2.

Fig. 4 is a view similar to Fig. 2 showing a modified spring means.

Fig. 5 is a detail of a modified spring member of rubber or similar resilient material.

Reference will be had to the disclosure in the Browning Patent 1,293,021 which discloses a standard U. S. machine gun. Fig. 1 is a reproduction of Fig. III of the Browning patent and in addition discloses one of a pair of coil springs or resilient means 10 resiliently separating barrel extension C' from breech bolt E'. The resilient means 10 produces sufficient force in the position shown in Fig. 1 to overcome the reaction spring R so as to move the breech bolt E' in its furthermost rear position against locking block N, that is to say that with the bolt in battery the

breech bolt has moved sufficiently rearward to take up all play in the parts.

In adjusting the Browning machine gun, it is necessary to thread the barrel B into the barrel extension C so far that, when the bolt E is in its forward locked position, no play between the bolt E and barrel extension C exists. This operation is commonly known as "adjusting the headspace." It has been found when play is permitted between these components, failure of the cartridge case by axial rupture, that is separation axially, is frequent. This failure is usually attributed to excess "headspace," that is, a too deep cartridge chamber, even when the headspace is only a few thousandths of an inch in excess of commonly accepted values. It is believed however, that this excess headspace is not the true cause of ruptures, as firings have been conducted, in non-automatic guns when the headspace was approximately 100 thousandths of an inch in excess, without failure of the cartridge case. These firings were conducted with the same lot of cartridges which had shown failures in a machine gun. Other known instances exist where the play was very accurately adjusted, but with a relatively large "headspace," no cartridge case failures occurred.

In explanation of the above performance applicant believes the cause of cartridge case failure resides in lost motion between the bolt E and barrel B when the bolt is not held firmly and against rearward movement in its locked position; and this lost motion is attributed to disparity in mating dimensions present when guns are made by production methods. On this basis, it is possible, when the mechanism goes forward prior to firing, for the bolt and cartridge to be jolted into and remain in their farthest forward positions with respect to the barrel. Upon firing, the propellant gas causes the cartridge case to expand and the forward end of the cartridge case being thinnest expands first and grips the chamber and thus releases the bullet; the ammunition cartridge gases then push the cartridge case to the rear. If the bolt E is not rigidly supported, it will move relative to the barrel B, and the cartridge case will elongate longitudinally as its rear end is pushed against the face of the bolt E while the front end is gripped by the barrel chamber wall. As, however, the walls of the cartridge case are cold worked and cannot withstand much distortion, the case may separate into two pieces.

It is important that the cartridge case be held firmly in the barrel, i. e., no movement of the

breech bolt E relative to barrel B should result when and as the cartridge is fired. Herein lies one important phase of the invention, namely, to provide means for firmly supporting the cartridge case against the breech bolt face and to secure the bolt E against movement relative to the barrel B so that gas pressure can act only to deform the shoulder and neck of the cartridge case whereby those elements tend to conform to the shape of the barrel chamber.

From the foregoing description it is apparent that the rupturing of cartridge cases may be prevented by insuring that the cartridge case and bolt are in their rearmost lock position before firing. This can be accomplished by means of springs or other expanding devices of low strength, which strength need only be sufficient to overcome the inertia and friction of the parts to be moved to their rearmost position and the initial force of the reaction spring R. These spring elements may be placed wherever the configuration of the parts conveniently permits; however, it appears most practical to place them within the rear end of the modified barrel extension, C' as seen in Fig. 2 to act with the rear downward extension of the modified breech bolt E'. It is noted that the modified barrel extension, C' and modified bolt E' have structure similar to that of corresponding elements in Fig. 1 and in the Browning Patent 1,293,021 and have identical functions. A pair of helical springs 10, 11 are shown in Fig. 3 but it is apparent that one or a plurality of leaf springs 12, Fig. 4, may be substituted for the helical springs 10, 11; or small cylinders 13 (Fig. 5) of highly elastic material such as rubber may also be employed instead of cylindrical helical springs 10, 11.

In Figs. 2 and 3 the springs 10, 11 are received and held in barrel extension recesses 14, 15. In Fig. 4 curled leaf spring 12 is held in the downwardly extending portion of breech block E'.

In the prior art practice as seen in the Browning Patent 1,293,021, the reaction spring R tends to move the bolt E as far forward as possible and barrel extension C is moved as far forward as possible by the tension of the spring on the piston Q. It is quite apparent that no means are disclosed in the Browning Patent 1,293,021 for taking up play and assuring positive engagement between the breech bolt E and locking block N; the spring devices or resilient means which overcome the effect of reaction spring R assure positive engagement of the bolt E against locking block N and thus positively maintain the bolt E and cartridge in their furthermore rear position with respect to the barrel B.

I claim:

1. In a firearm having a recoiling barrel and a rearwardly extending barrel extension, a breech bolt; means for locking the breech bolt and barrel extension together against relative axial movement in their firing position said locking means of the type subject to axial play when in locked position, and a spring urging the breech bolt forward; the improvement comprising resilient means interposed between the breech bolt and barrel extension and bearing directly on each,

and stronger than said spring when the latter is in expanded condition, said stronger resilient means being adapted to take up play between the breech bolt and barrel extension incident to the bolt locking means when said bolt and extension are in firing position, thus assuring that when said bolt and extension are in such position, the cartridge and bolt are in their furthermost rear position with respect to the barrel at the time of firing the cartridge.

2. In a firearm having a breech bolt, a recoiling barrel, a barrel extension, a locking block carried by the extension for locking the bolt and extension together against relative axial movement in firing position said locking means of the type subject to axial play when in locked position, means for actuating the block to effect such locking during the forward movement of said bolt and extension, and a breech bolt spring urging said bolt forward; the improvement comprising a separate spring interposed between the breech bolt and the barrel extension and bearing directly on each, and stronger than the breech bolt spring in its expanded condition and adapted to take up play between the breech bolt and barrel extension incident to the locking block when in locked position, thereby assuring engagement between the bolt and the barrel extension and the maintenance of the bolt and cartridge in the barrel in their furthermore rear position with respect to the barrel at the time of firing the cartridge.

3. In a firearm having a recoiling barrel having a cartridge case chamber allowing expansion of the cartridge case within the limits incident to the thermal condition in the cartridge case chamber when the cartridge is fired and a rearwardly extending barrel extension, a breech bolt, and means for locking the breech bolt and barrel extension together in their firing position said locking means of the type subject to axial play when in locked position, the improvement comprising resilient means directly engaging the barrel extension and bolt and urging the latter to its furthermost rear position by taking up the play in the bolt locking means, thus assuring that the cartridge as well as the bolt are in their furthermost rear position with respect to the barrel at the time of firing the cartridge.

4. In a firearm, a recoiling barrel having a chamber for insertion of a cartridge and a barrel extension having a rearwardly disposed face, a breech bolt slidably mounted in the barrel extension, a recoil spring urging said bolt to firing position, said bolt having a portion extending substantially parallel with the barrel extension face, bolt locking means carried by the barrel extension for locking the bolt and barrel extension together in firing position said locking means of the type subject to axial play when in locked position, and a spring stronger than the recoil spring when said recoil spring is in expanded position, said spring being interposed between said bolt portion and barrel extension face, bearing directly on each, and urging the bolt to its furthermost rear position against the bolt locking means at the time of firing the cartridge.

CHARLES E. BALLEISEN.
